UNITED STATES PATENT OFFICE

149,459

DESIGN FOR A COMBINATION RADIO AND TELEVISION CABINET

Victor Trad, Deal, N. J.

Application January 24, 1947, Serial No. 136,352

Term of patent 3½ years

(Cl. D56—4)

To all whom it may concern:

Be it known that I, Victor Trad, a citizen of the United States of America, residing at Deal, in the county of Monmouth, State of New Jersey, have invented a new, original, and ornamental Design for a Combination Radio and Television Cabinet, of which the following is a specification, reference being had to the accompanying drawing, forming part thereof.

In the drawing:

Figure 1 is a front elevational view of a radio and television cabinet, showing my new design. Figure 2 is a side elevation.

Figure 3 is a plan view.

I claim:

The ornamental design for a combination radio and television cabinet, as shown.

VICTOR TRAD.
